UNITED STATES PATENT OFFICE.

HUBERT D. TANNER, OF HARTFORD, CONNECTICUT, ASSIGNOR TO PRATT & WHITNEY COMPANY, OF NEW YORK, N. Y., A CORPORATION OF NEW JERSEY.

GEAR-FINISHING MACHINE.

Application filed March 26, 1927. Serial No. 178,598.

This invention relates to gear finishing machines and in particular to a machine for finishing the curved surfaces of teeth of spur or helical gears after they have 5 been suitably roughed out.

An object of the present invention is to provide a machine for finishing gears having oppositely disposed oscillating frames, each carrying a straight edged tool adapted to be actuated over the tooth curves of 10 a gear of the spur or helical type in the direction of the rolling movement of the gear.

Another object of the invention is to provide actuating means for the tool carried 15 by each of the oscillating frames which will effect a straight line movement of the cutting tool relative to its frame during the oscillatory movement of the frame.

A still further object of the invention 20 is to provide an adjustable cam for effecting the straight line movement of each of the cutters during the oscillation of its frame.

A still further object of the invention 25 is to provide means for advancing the position of the cam for each tool during operation of the machine in a direction to effect feeding movements of the tool during successive rotations of the gear blank.

A still further object of the invention 30 is to provide actuating means for the frames to simultaneously oscillate the frames so that the tools carried thereby will be moved simultaneously over the tooth curves of the gear being finished.

With these and other objects in view my invention consists in the features of construction and operation set forth in the 40 following specification and illustrated in the accompanying drawings.

In the accompanying drawings annexed hereto and forming a part of this specification, I have shown my invention embodied 45 in a gear finishing machine, but it will be understood that the invention can be otherwise embodied and that the drawings are not to be construed as defining or limiting the scope of the invention, the claims appended to this specification being relied 50 upon for that purpose.

In the drawings:

Figure 1 is a front elevation of a complete machine made according to the pres-

ent invention, parts being shown in section to more clearly show their construction.

Fig. 2 is an end elevation, partly in section, of a complete machine.

Fig. 3 is a sectional view on an enlarged scale taken substantially upon line 3—3 of Fig. 1 and showing the arrangement of the oscillating frames and parts associated therewith.

Fig. 4 is a plan view taken on the line 4—4 of Fig. 1 and showing the oscillating frames in their upper and outer positions.

Fig. 5 is an end view of a part of the machine showing the spindle indexing mechanism.

Fig. 5^a is a detail of the indexing mechanism.

Fig. 6 is a rear view of the indexing mechanism shown in Fig. 5.

Fig. 7 is a view similar to Fig. 5 showing another part of the spindle indexing mechanism.

Fig. 8 is a sectional view taken on line 8—8 of Fig. 1 showing a part of the cam advancing mechanism for effecting feeding movements of the tools.

Fig. 9 is a detail sectional view of the starting and stopping mechanism for the machine.

Fig. 10 is a plan view taken on line 10—10 of Fig. 9, and

Fig. 11 is an end view of the actuating means for advancing the tool controlling cams.

In the above mentioned drawings I have shown but one embodiment of the invention 90 which is now deemed preferable, but it is to be understood that changes and modifications may be made within the scope of the appended claims without departing from the spirit of the invention.

Briefly, and in its broadest aspect, my invention comprises the following principal parts: First, a base; second, a work supporting spindle mounted for rotation preferably upon a horizontal axis; third, a pair 100 of oppositely disposed frames adapted to oscillate about the axis of the work supporting spindle; fourth, tool supports adjustably mounted on the frames for movement in a direction parallel to the axis of 105 the work spindle; fifth, a tool head on each of the supports movable in a straight line normal to the direction of adjustment of its

support; sixth, cams mounted above the frame and adapted to actuate the tool heads during oscillatory movement of the frame; seventh, means to individually adjust the cams to vary the movement of the tool and vary the effect of the tool upon the gear being cut; eighth, means to slightly advance the cam after each complete rotative movement of the work spindle; ninth, means to oscillate said frames; and tenth, means to index said work spindle between oscillatory movements of said frames to engage successive teeth of the gear with the tools.

Referring more in detail to the figures of the drawings, I provide a base 10 having mounted therein a spindle 11 upon which work W may be mounted at its inner end. Means to index this spindle 11 to successive angular positions is provided, preferably mounted as shown upon the outer end of the work spindle 11. This indexing mechanism for the spindle 11 shown in Figs. 5, 6 and 9 comprises a notched plate 12 rigidly secured to the outer end of the work spindle 11 by the connections shown in Fig. 5^a so that this plate 12 may be slightly adjusted relative to the spindle 11. A plunger 13 is slidable within the base and is adapted to engage within the notches of the plate 12 to rigidly secure the spindle 11 in each indexed position. In order to effect indexing movements of the spindle 11, which occur between successive oscillatory movements of frames 14 presently to be described, a toothed disk adjacent and forming part of the disk 12 is mounted on the outer end of the work spindle 11 and is adapted to be engaged by a pawl 15 carried upon an oscillating arm 20. Cams 16 and 17, preferably mounted on a constantly rotating shaft 18 in the base 10 of the machine, are provided for oscillating the pawl 15 and its arm 20 predetermined distances and for locking the plunger 13 in timed relation to each other. A third cam 21 controls the movement of the pawl carrying lever 22.

It will be understood that any desired form of spindle indexing mechanism may be provided of conventional or usual form, the one shown being adapted to provide simple means to rotate and lock the spindle 11 by cams 16 and 17. By providing a notched disk 12 having notches corresponding to the number of teeth in the gear W being finished and adjusting the position of a reach arm 19 on the lever 20 carrying the pawl 15, the indexing mechanism can be adjusted for a gear having any number of teeth.

As shown in Fig. 1, the cams 16, 17 and 21 are mounted on the shaft 18 which forms the main driving shaft of the machine. This shaft 18 is driven from a worm gear 23 thereon which may be driven from a worm 24 on a shaft 25 driven from a suit-

able motor 26. On the shaft 25 may be mounted a starting clutch 27 indicated as of the tooth type. This may be operated by a yoke 28 engaging a groove in its movable member adapted to be actuated from a hand lever 30. Means to disengage the clutch 27 at the end of the cycle of operations of the machine will presently be described.

Mounted for oscillatory movement on the machine are the two U-shaped frames 14, 75 their axes of oscillation coinciding with the axis of the work supporting spindle 11. In order to oscillate these frames 14, connecting rods 32 are secured to the frames preferably in a manner to permit adjustment toward 80 and from the axis of oscillation so that the oscillatory movement of the frames 14 may be widely varied. This connection between the frames 14 and the rods 32 is clearly shown in Fig. 2 and comprises a screw 33 85 rotatably mounted in the frame 14. A nut 34 engaging this screw 33 forms the upper end of the rod 32. By rotating the screw 33 and traversing the nut 34 toward and from the axis of oscillation of the frame 14, 90 the oscillatory movement may be widely varied. The rods 32 are also made adjustable in length by being formed in two parts joined by means of a turn buckle 36. These connecting rods 32 at their lower ends are 95 provided with rollers which contact with cams 35 mounted on the slowly rotating drive shaft 18 within the base 10. As shown in Figs. 1 and 2, these cams 35 are so disposed upon the shaft 18 that oscillatory 100 movement of the frames 14 occurs in reverse direction exactly simultaneously so that tools mounted on these frames 14 will simultaneously perform their cutting operation upon opposite surfaces of different 105 gear teeth.

Mounted on planed surfaces on the frames 14 in a manner to permit adjustment in directions parallel to the axis of oscillation of the frames are tool supports 40, one being 110 provided on each frame. These supports 40, as shown in Fig. 3, may be provided with a tongue 41 engaging a groove formed in the frame 14, bolts 42 being provided extending through elongated slots in the 115 supports 40 for adjustably securing them in proper position for operation upon any form of gear blank. Mounted on these tool supports 40 are tool heads 45 slidably movable in a straight line in a direction normal to the direction of adjustment of the supports 40 and obliquely toward and from the axis of oscillation of the frames 14. Normally these heads 45 are forced by a spring 46 to a position away from the axis of oscillation 120 of the frames 14 and are made of two parts, the tool holding part 45 being adjustable relative to a part 47 engaging a guideway in the tool support 40. By means of suitable securing means (not shown) these two parts 130

45 and 47 may be clamped rigidly in position.

In order to actuate these tool heads 45 in a straight line toward and from the axis of oscillation of the frames 14 during oscillatory movements of the frames 14, rollers 48 are mounted upon the members 47 of the heads 45 adapted to contact with suitable cams 49 adjustably secured to a frame 10 mounted on the upper portion of the machine. It will be seen from this construction that during oscillatory movement of the frames 14 each tool head 45 is advanced along the guideways in its tool support 40 a distance depending upon the contour of the cam 49. On one member 45 of each tool head is mounted an oscillatory tool block 50 having a tool 51 with a straight cutting edge in the present instance extending parallel to the axis of the work support 40 and axis of oscillation of the frame 14. This tool 51 may be clamped, as shown, to the tool block 50 by any desired means.

In order to effect feeding movements of the tool 51 relative to the gear blank W being finished, the cams 49 are mounted upon a transverse arm 55 by means of eccentric journals 56 so that the cams 49 may be very slightly advanced by movement of the arm 55 toward the work spindle 11. In order to effect this feeding movement of the cams 49 the eccentric journals or spindles 56 are provided with levers 57 suitably connected together by a reach arm 58 so that they will operate together. One of the levers 57 is provided with a reach rod 59 extending to a cam plate 60 mounted on a slowly rotating shaft 61 within the base 10 of the machine. After each complete rotation of the work spindle 11, the reach rod 59 is forced upwardly a slight amount by engagement of its roller 62 with the cam 60, thus oscillating the levers 57 and the eccentric portions of the spindles 56 to slightly lower the arm 55 on which the cams 49 are mounted.

As shown in Fig. 2, the shaft 61 is rotated from the shaft 18 by a worm gear 65 engaging a worm on shaft 18. The worm gear 65 is on a shaft 66 adapted to drive the shaft 61 through spur gears 67 disposed on the ends of these shafts so that they may readily be changed. By choosing the proper ratio of gears 67 the shaft 61 and its cam 60 may be made to rotate exactly once during a complete cycle of operations of the machine.

A cam 60 is shown in its outline in Fig. 11 by which it will be seen that the reach rod 59 is raised slightly at three different times during the cycle of operation of the machine. This is to effect three separate feeding movements of the tools 51 preferably while the work spindle 11 and the work W are rotated through three complete revolutions.

In operation the machine, which normal-

ly is provided with a pair of oppositely disposed frames, simultaneously forces the frames from the position shown in Fig. 3 in full lines to upper position as shown in dotted lines. The effect of this movement, therefore, is to move the tool in the arc of a circle. Simultaneously with this movement, however, the action of the cam upon the roller on the tool head is such that a slight movement toward the axis of the work support is effected. The result of this combined movement of the tool is an involute or other curve on the tooth of the gear blank being finished. The precise curve upon which the tool is actuated depends upon the particular contour of the cam engaging the roller. It will be seen, therefore, that by suitably varying the contour of the cams, various tooth curves may be formed on the gear blank differing from or coinciding exactly with an involute.

At the completion of operation of the machine upon a work blank W it is desirable to stop all of the operative movements of the machine. Means are therefore provided preferably associated with the clutch 27 to open this clutch when the shaft 61 has completed one revolution. By starting the machine by lever arm 30, shaft 70 is oscillated which oscillates the clutch yoke 28 through a spring 71 bearing against an arm 72 pinned to the shaft carrying the yoke 28. In the operative or closed position a detent 73 engages a notch in the arm 72 thus preventing the clutch from opening. A cam 74 on shaft 100 61 has a projection which, as soon as operation is completed, withdraws the detent 73 from the arm 72, thus allowing the spring 71 to expand and force the clutch yoke 28 to oscillate in a direction to open the clutch 27. The machine therefore comes to rest and may be again started by means of the lever 30.

What I claim is:

1. A gear finishing machine comprising in combination, a base, an oscillatory frame adapted to oscillate about a fixed axis, means to oscillate said frame between fixed points, a work spindle mounted for rotation on a fixed axis on said base, means to index said spindle between oscillatory movements of said frame, a tool head slidable on said frame, a cam secured to the base, means on said tool head engaging said cam whereby said tool head is moved along the frame during oscillatory movement of said frame, and means to adjust said cam to vary the path of movement of said tool head.

2. A gear finishing machine comprising in combination, a base, oppositely disposed oscillatory frames adapted to oscillate about a common fixed axis, means to oscillate said frames between fixed points, a work spindle mounted for rotation on said base, means to index said spindle between oscillatory move-

- ments of said frames, a tool head slidable on each of said frames, cams secured to the base, and means on said tool heads respectively engaging said cams whereby said tool heads are moved along the frames during oscillatory movements of said frames. 5
3. A gear finishing machine comprising in combination, a base, oppositely disposed oscillatory frames adapted to oscillate about 10 a common fixed axis, means to simultaneously oscillate said frames between fixed points, a work spindle mounted for rotation on said base upon the same axis as said frames, means to index said spindle between oscillatory movements of said frames, a tool head slidable on each of said frames in a direction toward and from the axis of said spindle, cams secured to the base, and means 15 on said tool heads engaging said cams whereby said tool heads are simultaneously moved during oscillatory movement of said frames. 20
4. A gear finishing machine comprising in combination, a base, oppositely disposed oscillatory frames adapted to oscillate about a common fixed axis, means to simultaneously oscillate said frames in opposite directions between fixed points, a work spindle mounted for rotation on said base 25 upon the same axis as said frames, means to index said spindle between oscillatory movements of said frames, a tool head slidable on each of said frames in a direction toward and from the axis of said spindle, cams secured to the base, and means on said 30 tool heads engaging said cams whereby said tool heads are moved during oscillatory movement of said frames. 35
5. A gear finishing machine comprising 40 in combination, a base, a work spindle on said base, an oscillatory frame adapted to oscillate about a fixed axis, means to oscil-
- late said frame between predetermined points, a tool head slidable on said frame, a cam fixed to the base, means on said tool head engaging said cam whereby said tool head is moved in said frame toward and from the axis of said spindle, and means to advance said cam to effect feeding movements of said tool head. 45
6. A gear finishing machine comprising in combination, a base, oppositely disposed oscillatory frames adapted to oscillate about a common fixed axis, means to oscillate said frames between fixed points, a work spindle mounted for rotation on said base, means to index said spindle between oscillatory movements of said frames, a tool head slidable on each of said frames, a cam secured to the base, means on said tool 50 heads engaging said cam whereby said tool heads are moved in a straight line during oscillatory movement of said frames, and means to advance said cam to effect feeding movements of said tool heads. 55
7. A gear finishing machine comprising in combination, a base, oppositely disposed oscillatory frames adapted to oscillate about a common fixed axis, means to oscillate said frames between fixed points, a work spindle 60 mounted for rotation on said base upon the same axis as said frames, means to index said spindle between oscillatory movements of said frames, a tool head slidable on each of said frames in a direction toward and 65 from the axis of said spindle, cams secured to the base, means on said tool heads engaging said cams whereby said tool heads are moved during oscillatory movement of said frames, and means to advance said cams to 70 effect feeding movements of said tool heads. 75
- In testimony whereof, I hereto affix my signature.

HUBERT D. TANNER.
